DESIGN FOR A FOUNDATION GARMENT

Esther Uslaner, Jackson Heights,
Long Island, N. Y.

Application May 14, 1940, Serial No. 92,365

Term of patent 3½ years

To all whom it may concern:

Be it known that I, Esther Uslaner, a citizen of the Union of Soviet Socialist Republics, and resident of Jackson Heights, Long Island, in the county of Queens and State of New York, have invented a new, original, and ornamental Design for a Foundation Garment, of which the following is a specification, reference being had to the accompanying drawing, forming a part thereof.

Fig. 1 is a front elevational view of a foundation garment, showing my new design.

Fig. 2 is a side elevational view of the same.

Fig. 3 is a rear elevational view of the same.

I claim:

The ornamental design for a foundation garment, as shown.

ESTHER USLANER.
